UNITED STATES PATENT OFFICE

147,721

DESIGN FOR A TABLE LAMP BASE

Nils Ericsson, New York, N. Y.

Application May 28, 1946, Serial No. 130,154

Term of patent 7 years

(Cl. D48—20)

To all whom it may concern:

Be it known that I, Nils Ericsson, a citizen of the Kingdom of Sweden and resident of the city of New York, county of Bronx, and State of New York, have invented a new, original, and ornamental Design for a Table Lamp Base, of which the following is a specification, reference being had to the accompanying drawing, forming part thereof.

Fig. 1 is a front elevation of a table lamp base, showing my new design;

Fig. 2 is a view at right angles to Fig. 1, and Fig. 3 is a plan view of the table lamp base. The dominant features of my design reside in the portions shown in full lines.

I claim:

The ornamental design for a table lamp base, substantially as shown and described.

NILS ERICSSON,
